UNITED STATES PATENT OFFICE

165,128

ARTIST'S PALETTE OR THE LIKE

George J. Blacher, Pasadena, Calif.

Application June 8, 1950, Serial No. 10,400

Term of patent 14 years

(Cl. D74—1)

To all whom it may concern:

Be it known that I, George J. Blacher, a citizen of the United States, and residing at Pasadena, in the county of Los Angeles and State of California, have invented a new, original, and ornamental Design for an Artist's Palette or the like, of which the following is a specification, reference being had to the drawing, forming part thereof.

In the drawing:

Figure 1 is a view in perspective of an artist's palette or the like embodying my new design; and

I claim:

The ornamental design for an artist's palette or the like, substantially as shown.

GEORGE J. BLACHER.
